UNITED STATES PATENT OFFICE.

JAMES V. WASHBURNE, OF WATERBURY, CONNECTICUT.

DESIGN FOR A SAFETY-PIN.

SPECIFICATION forming part of Design No. 34,891, dated August 6, 1901.

Application filed May 6, 1901. Serial No. 59,054. Term of patent 14 years.

To all whom it may concern:

Be it known that I, JAMES V. WASHBURNE, a citizen of the United States, residing at Waterbury, in the county of New Haven and State 5 of Connecticut, have invented and produced a new and original Design for a Safety-Pin, of which the following is a specification, reference being had to the accompanying drawing, forming part thereof.

10 In the drawing I have represented my new design for a safety-pin by an elevation.

The leading or essential feature of my design consists in the ornamental shape and configuration of the bar *a*, which at the central portion is bent and in outline represents 15 substantially the letter **W**.

The design of the safety-pin comprises, with the shield *b* at one end, the eye-band *c* at the other end thereof, and the pointed pin-bar *d*,

the curved and downward-extending parts 2 20 *2* closely adjacent to the eye-band *c* and shield *b* and forming part of the bar *a*, and the downwardly and upwardly extending parts *4* therefrom and intermediate thereto also forming parts of the ornamental bar *a* and in outline representing substantially the letter **W**, 25 the ends of which terminate at the curved parts *2* *3*.

What I claim as new is—

The design for a safety-pin as herein shown 30 and described.

In testimony whereof I have signed my name to this specification in the presence of two subscribing witnesses.

JAMES V. WASHBURNE.
